UNITED STATES PATENT OFFICE.

ROBERT U. DONAL, OF EMMET, ARKANSAS, ASSIGNOR OF ONE-FOURTH TO
H. STANTON, OF SAME PLACE.

WELL-BORING MACHINERY.

SPECIFICATION forming part of Letters Patent No. 340,562, dated April 27, 1886.

Application filed January 29, 1886. Serial No. 190,151. (No model.)

To all whom it may concern:

Be it known that I, ROBERT U. DONAL, a citizen of the United States, residing at Emmet, in the county of Nevada and State of Arkansas, have invented certain new and useful Improvements in Well-Boring Machinery, consisting of drill, trimmer, and sand-pump combined; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention has relation to well-augers; and it consists of a drill, trimmer, and sand-pump, as hereinafter fully described and set forth.

The drill can be used without the sand-pump, or the sand-pump can be used without the drill, or they may be used conjointly.

In the accompanying drawings, Figure 1 is a view showing my invention ready for use. Fig. 2 is a sectional view of the same, cut on the line *x x*. Fig. 3 is a view of my invention when opened to empty the sand. Fig. 4 is a top plan view of the top plate. Fig. 5 is a top view of the bottom plate. Fig. 6 is a view of the lower face of the bottom plate. Fig. 7 is a view of the drill-rod.

Similar figures refer to similar parts throughout the several views.

My invention is described as follows: By means of the two upright pieces 1 and 2 I secure together the top plate, 3, and bottom plate, 4, thus making a skeleton frame, to which are secured the two half-cylindrical doors 5 and 6. The door 5 has one of its edges securely bolted or riveted to the upright 1 by means of the bolts or rivets 7, and the door 6 has one of its sides bolted or riveted to the upright 2 by means of bolts or rivets 8. From either end of the uprights 1 and 2 project threaded necks 9, on which are screwed nuts 10, said nuts holding said top and bottom plates in position. The said threaded necks are smaller than the uprights proper, and thus make shoulders on the uprights 1 and 2, against which the perforated plates 3 and 4 rest. The said uprights are pivoted in perforations in

said plates, and only one edge of the said half-cylindrical doors being bolted to said uprights enables the same to open and shut, and when so closed they form a perfect hollow cylinder. 55 The free edges of said half-cylindrical doors are provided with perforated laps or tongues 11, said laps fitting into corresponding depressions, 12, in the opposite side, and the edges of the said doors along the line of their junction are flush. When the said half-cylindrical doors are shut, they are held in position by means of screw-bolts passing through said laps and screwing into female screws in said uprights. The heads of said screw-bolts 65 are also countersunk. These doors 5 and 6 may be held closed by two screw-bolts, one at the top and one at the bottom of each door.

In the top plate, 3, I provide perforations 13, through which the air and water may be forced as fast as the solid material enters the body of the pump through the openings in the bottom. I make as many of these perforations as may be found necessary.

On the lower side of the bottom plate, 4, I 75 secure two trimmers, 14 and 15, said trimmers being secured to said plate by rivets, or in any secure manner, each trimmer being curved to correspond to the curve of the periphery of the said plate, and when fitted to the same makes 80 a smooth joint. On the top face of the said perforated bottom plate, 4, I rivet self-closing valves, composed of rubber cloth, 16, or other suitable material, and having secured to the loose sides two plates of metal, 17 and 18, which 85 fit in the lower end of said cylinder and serve to stiffen said valves.

The drill may be used without the pump, or the pump may be used without the drill, or they may be used conjointly.

In case it is desired to use the drill only, the pump is removed by unscrewing the drill-point 20 and the top ring or rope-holder 21, when the pump may be removed. Then replace the said point 20, drill-section 19, and ring or 95 rope-holder 21, and the drill is again ready for use. The ring or rope-holder 21 at the top of the combination can be removed, and as many drill-sections as are necessary can be attached to the drill-section 19, and the rope-holder reattached, and the drill is again ready 100 for use. I also provide for fastening the trim-

mers 14 and 15 to the edge of the said bottom plate, 4, if such a course should be found necessary.

Having described my invention, what I claim as new, and desire to secure by Letters Patent, is—

1. The combination of the perforated plates 3 and 4, uprights 1 and 2, pivoted in said plates, doors 5 and 6, secured to said uprights, and valves 17 and 18, hinged on the upper face of the perforated plate 4, substantially as shown and described.

2. In a sand-pump, as above described, the trimmers 14 and 15, secured to the lower plate, 4, substantially as shown and described.

3. In a sand-pump, as above described, the cylindrical doors 5 and 6, secured to the pivoted uprights 1 and 2, and having tongues or laps 11 and depressions 12, substantially as

shown and described, and for the purposes set forth.

4. In a combined drill, sand-pump, and trimmer, the combination of the said pump having the valves 17 and 18, trimmers 14 and 15, and hinged doors 5 and 6, with drill-section 19, pivoted in the center perforations of the plates 3 and 4, rope-holder 21, screwed on the upper end of said drill-section, and drill-point 20, screwed on the lower end of the same, substantially as shown and described, and for the purposes set forth.

In testimony whereof I affix my signature in presence of two witnesses.

ROBERT U. DONAL.
